UNITED STATES PATENT OFFICE.

CARL GRETER, OF TODTNAU, GERMANY.

BRUSH.

Application filed March 11, 1926, Serial No. 93,936, and in Germany March 20, 1925.

This invention relates to an improved brush or broom, and the novelty consists in that the folded bristle tufts forced through straight apertures in the bristle supporting back of the brush or broom are fixed each by means of a looped wire encircling the bight of the tuft and having its ends tangential to the loop while engaging the rear portion of the bristle supporting back to prevent outward displacement of the said bristle tuft, a binding wire running over the upper surface of the bristle supporting back and passing successively through said looped wires. Besides, said tufts may be connected with the lower side of the bristle supporting back by means of a binding agent.

Said double binding permits the use of a bristle supporting back of very thin material, such as wood, sheet-metal, or the like.

The accompanying drawing illustrates the improvements in fragmentary sectional views of a bristle supporting back with the bristle tufts attached thereto: Fig. 1 showing a thin wooden bristle supporting back, Fig. 2 a sheet-metal back, and Fig. 3 the attachment by means of a binding agent.

As shown in Fig. 1, the bristle supporting back *a* is provided with straight apertures *b* into which the folded bristle tufts *d* enclosed by looped wires *c* are forced, the ends of said wires being tangential to the loops and engaging the rear portion of the back to prevent outward displacement of the bristle tufts. A binding wire *e* running over the upper surface of the back *a* and successively passing through the looped wires *c* prevents a displacement of the bristle tufts in downward direction.

As shown in Fig. 2, the binding on sheet-metal backs *a'* is effected by punching there-

in the holes *b'* whereby a burr *f* is provided on the lower side of the back on which bear the tangential ends of the looped wires *c'* after the bristle tufts *d'* enclosed by said loops have been forced therein. A downward displacement of the bristle tufts is prevented by means of a binding wire *e'* running over the upper surface of the back *a'* and successively passing through the single loops *c'*.

The forcing in of the bristle tufts enclosed by the loops and of the binding wire is suitably effected in one working process.

As shown in Fig. 3, the downward displacement of the bristle tufts *d''* can also be prevented by connecting the latter with the lower side of the back *a''* by means of a binding agent *g*. Said latter expedient can be used in combination with the binding wire *e''* running over the upper surface of the back and successively passing through the single loops.

What I claim, is:—

1. A brush, comprising a bristle supporting back having a plurality of bristle receiving apertures, folded tufts of bristles in said apertures, each tuft having a looped wire encircling its bight, said wire having its ends tangential to the loop and engaging the rear portion of the back to prevent outward displacement of said bristle tuft, and a binding wire running over the upper surface of the back and successively passing through said looped wires. 75

2. In a brush as specified in claim 1, a binding agent connecting said bristle tufts with the lower side of said bristle supporting back.

In testimony whereof I have hereunto set my hand.

CARL GRETER.
